Maurice P. Owens

Application December 6, 1950, Serial No. 13,288

Term of patent 14 years

(Cl. D44—10)

To all whom it may concern:

Be it known that I, Oscar G. Lilja, a citizen of the United States, residing at Rockford, in the county of Winnebago and State of Illinois, have invented a new, original, and ornamental Design for a Serving Stand, of which the following is a specification, reference being had to the accompanying drawings, forming a part thereof.

In the drawings:

Fig. 2 is a top plan view; and

Fig. 3 is a front elevational view.

The dominant features of my design reside in the portion drawn by means of full lines in the accompanying drawings.

I claim:

The ornamental design for a serving stand, substantially as shown and described.

OSCAR G. LILJA.
